QUATERNARY SALTS OF CHLORPHENOXY METHYLAMINES

5 Harry James Barber, Gidea Park, and Maurice Berkeley Green, Hornchurch, England, assignors to May & Baker Limited, Dagenham, England, a company of Britain

No Drawing. Application September 5, 1952,
Serial No. 308,158

Claims priority, application Great Britain May 25, 1949

2 Claims. (Cl. 260—567.6)

This application relates to new and valuable quaternary salts and is a continuation-in-part of our application Serial No. 163,568 filed May 22nd, 1950, now abandoned.

It is an object of this invention to provide valuable new surface-active bactericides. It is a further object of this invention to provide a narrow class of quaternary salts which in their bactericidal action are of outstanding merit and of exceptional utility compared with compounds of related chemical constitution.

It is a further object to provide a process for the production of such compounds.

We have prepared and have investigated the properties of a whole series of quaternary salts of the hitherto unknown phenoxyethylamines possessing the constitution:

where R represents a member of the class consisting of phenyl, phenylene and naphthyl and phenyl and naphthyl radicals substituted by at least one of cyano, nitro, halogen, lower alkyl and lower alkoxy, Y represents a member of the class consisting of chlorine and bromine, R₁, R₂ and R₃ are selected from the class consisting of individual groups and a common ring system such that when R₁, R₂ and R₃ represent individual groups, R₁ is a member of the class consisting of alkyl, aralkyl and cycloalkyl radicals, R₂ and R₃ each represent alkyl groups containing not more than four carbon atoms and when R₁, R₂ and R₃ represent a common ring system they together represent the residue of a heterocyclic tertiary amine, and n is an integer not greater than 2.

We have made the surprising discovery that compounds of the above formula in which R represents a member of the class consisting of phenyl and lower alkyl substituted phenyl substituted in the nucleus by at least one chlorine

TABLE I

Comparison of bacteriostatic efficiencies of phenoxyethyl-dimethyl-octylammonium chlorides and phenoxy-methyl-dimethyl-benzyl ammonium chlorides

	Minimum effective dilutions against—		
	<i>Staph. aureus</i>	<i>B. coli</i>	<i>Ps. pyocyanea</i>
4-chloro-3:5-dimethyl phenoxyethyl-dimethyl-n-octylammonium chloride.....	1:1,024,000	1:16,000	1:8,000
4-chloro-3:5-dimethyl phenoxyethyl-dimethyl-benzylammonium chloride.....	1:32,000	1:4,000	1:2,000
4-chloro-3-methyl phenoxyethyl-dimethyl-benzylammonium chloride.....	1:16,000	1:4,000	1:2,000
Phenoxyethyl-dimethyl-benzylammonium chloride.....	1:2,000	1:2,000	1:2,000

2

TABLE II

Comparison of bacteriostatic efficiencies of phenoxyethyl-dimethyl-octylammonium chlorides and phenoxy-methyl-pyridinium chlorides

		Minimum effective dilutions against—		
		<i>Staph. aureus</i>	<i>B. coli</i>	<i>Ps. pyocyanea</i>
2:4 - Dichlorophenoxyethyl-dimethyl-n-octylammonium chloride.....	1:512,000	1:16,000	1:8,000	
2:4 - Dichlorophenoxyethyl-pyridinium chloride.....	1:8,000	1:2,000	1:2,000	

atom, R₁ represents a member of the class consisting of alkyl groups having more than six carbon atoms, n is one, and R₂, R₃ and Y have the significance defined above, possess remarkably high activities as surface-active bactericides and are especially suitable for use as topical antisepsics for the sterilisation of skin and surgical instruments. The exceptional utility of this particular group of compounds as compared with members of the wider group having the aforesaid general formula is exemplified by the comparison of bacteriostatic efficiencies detailed in Tables I and II.

Moreover, quaternary salts of the present invention show marked advantage over prior art compounds by virtue of the fact that their bacteriostatic efficiency is only slightly reduced in the presence of blood or serum as illustrated in Tables III and IV and that, in skin sterilisation, they are effective against both gram-positive and gram-negative organisms, in particular, *Pseudomonas pyocyanea*, as illustrated in Table V.

TABLE III

Comparison of bacteriostatic efficiency of 4-chloro-3:5-dimethyl phenoxyethyl-dimethyl-n-octylammonium chloride with that of other quaternary salts against *Staph. aureus* in blood

	Minimum effective dilution	
	<i>Staph. aureus</i> in broth	<i>Staph. aureus</i> in blood
4-chloro-3:5-dimethyl-phenoxyethyl-dimethyl-n-octylammonium chloride.....	1:1,024,000	1:256,000
β -phenoxyethyl-dimethyl-dodecylammonium chloride.....	1:1,024,000	1:32,000
Cetyltrimethyl ammonium bromide.....	1:1,024,000	1:16,000

TABLE IV

55 Comparison of sterilising efficiency of 4-chloro-3:5-dimethyl phenoxyethyl-dimethyl-n-octylammonium chloride with that of other quaternary salts against *B. coli* in milk

		Time for complete sterilization at concentration of 1:1,000
4-chloro-3:5-dimethyl-phenoxyethyl-dimethyl-n-octylammonium chloride.....		One minute.
β -phenoxyethyl-dimethyl-dodecylammonium chloride.....		Five minutes.
Cetyltrimethyl ammonium bromide.....		More than five minutes.

3
TABLE V

Comparision of sterilising efficiencies of phenoxyethyl-dimethyl-octylammonium chlorides with that of other quaternary salts against *Ps. pyocyanea* on skin

	Number of colonies of <i>Ps. pyocyanea</i> remaining thirty seconds after sterilisation with a 1 percent solution
4-chloro-3:5-dimethyl-phenoxyethyl-dimethyl-n-octylammonium chloride	Nil
2:4-dichlorophenoxyethyl-dimethyl-n-octylammonium chloride	Nil
β -phenoxyethyl-dimethyl-dodecylammonium chloride	8
Cetyltrimethylammonium bromide	13

The quaternary salts of the present invention are prepared by reacting a phenoxyethyl halide of the type ROCH_2Y with a tertiary amine of the type $\text{NR}_1\text{R}_2\text{R}_3$ where Y , R , R_1 , R_2 and R_3 have the significance hereinbefore defined. Condensation of the phenoxyethyl halide and tertiary amine may be readily effected by mixing the reactants at room temperature either alone or in the presence of a suitable solvent or diluent. An exothermic reaction takes place within a short time. After the initial reaction is over the mixture is heated to 80-100° C. for a short time and the quaternary salt isolated by filtration, crystallisation, extraction, evaporation or any other suitable method. Equimolecular proportions of the reactants are generally used but an excess of the tertiary amine may be used if desired. The reaction solvent may be one in which the quaternary halide is soluble such as water, ethyl alcohol or chloroform or one in which the quaternary halide is insoluble such as benzene or ether. The quaternary salts may be crystallised from a mixture of ethyl acetate and chloroform.

The invention is illustrated by the following non-limitative example:

0.51 g. 3:5-dimethyl-4-chloro-phenoxyethyl chloride and 0.40 g. dimethyl-n-octylamine are mixed with 1 cc. benzene. The temperature rises to 35° C. and a white solid separates. After 15 minutes the mixture is heated on the steam-bath for 5 minutes under reflux. The solid is filtered off, washed with benzene and recrystallised from a mixture of chloroform and ethyl acetate, giving 0.65 g. (3:5 - dimethyl - 4 - chloro-phenoxyethyl) - dimethyl-n-octyl-ammonium chloride, M. P. 162.0-163.5° C.; 72% yield.

In a similar manner are prepared:

	Melting point, °C.
3:5 - dimethyl-4-chlorophenoxyethyl-dimethyl-iso-octyl ammonium chloride	117-125
3:5 - dimethyl-4-chlorophenoxyethyl-dimethyl-n-decyl ammonium chloride	152-153
3:5 - dimethyl-4-chlorophenoxyethyl-dimethyl-lauryl ammonium chloride	143-144
3:5 - dimethyl-4-chlorophenoxyethyl-dimethyl-cetyl ammonium chloride	140-143
3:5 - dimethyl-4-chlorophenoxyethyl-dimethyl-stearyl ammonium chloride	144-147
2:4-dichlorophenoxyethyl-dimethyl - n - octyl ammonium chloride	145-146
2:4-dichlorophenoxyethyl-dimethyl - n - decyl ammonium chloride	135-136
2:4 - dichlorophenoxyethyl - dimethyl - stearyl ammonium chloride	129-131

The surface-active bactericides of the present invention are employed in the pharmaceutical forms customary for topical antiseptics. Thus, normally, these compounds will be employed in solution form, employing a solvent such as water. However, it will be understood, that other pharmaceutical presentations, such as ointments and the like, containing active substances are within the purview of this invention.

We claim:

1. Quaternary salts of phenoxyethylamines of the general formula

where X represents at least one and at most two nuclear chlorine substituents and Z is selected from the class consisting of hydrogen and lower alkyl nuclear substituents, R_1 represents a member of the class consisting of alkyl groups having more than six carbon atoms, R_2 and R_3 are alkyl groups containing up to four carbon atoms and Y is selected from the class consisting of chlorine and bromine.

2. A process for the production of quaternary salts of phenoxyethyl-amines which comprises reacting a compound of the formula

with an amine of the formula $\text{NR}_1\text{R}_2\text{R}_3$, where X represents at least one and at most two nuclear chlorine substituents and Z is selected from the class consisting of hydrogen and lower alkyl nuclear substituents, R_1 represents a member of the class consisting of alkyl groups having more than six carbon atoms, R_2 and R_3 are alkyl groups containing up to four carbon atoms and Y is selected from the class consisting of chlorine and bromine.
